Kurgo Wander Collar web-site, Dec. 10, 2009, www.kurgo.com/products/wcol.html, Author Unknown.*Primary Examiner* — Susan Moon Lee(74) *Attorney, Agent, or Firm* — Wolff Law Office, PLLC;
Kevin Alan Wolff(57) **CLAIM**

I claim the ornamental design for a collar for a dog, as shown and described.

DESCRIPTION

FIG. 1 is a front perspective view of a collar for a dog, shown in a closed position;

FIG. 2 is a front view of the present invention shown in a closed position.

FIG. 3 is a bottom view of the present invention shown in a closed position.

FIG. 4 is a left side bottom view of the present invention shown in a closed position; and,

FIG. 5 is a rear view of the present invention shown in a closed position.

The broken lines showing a snapping or fastening buckle and a length adjustment slip buckle in all the figures are for illustrative purposes only and forms no part of the claimed design.
